UNITED STATES PATENT OFFICE.

CHARLES W. KIRSCH, OF STURGIS, MICHIGAN, ASSIGNOR TO KIRSCH MANUFACTURING COMPANY, OF STURGIS, MICHIGAN, A CORPORATION OF MICHIGAN.

CHANNELED STRIP SUCH AS CURTAIN RODS OR THE LIKE

Application filed February 4, 1924. Serial No. 690,519.

To all whom it may concern:

Be it known that I, CHARLES W. KIRSCH, a citizen of the United States, and a resident of Sturgis, in the county of St. Joseph and State of Michigan, have invented certain new and useful Improvements in Channeled Strips Such as Curtain Rods or the like, of which the following is a specification.

10 This invention relates to the manufacture of articles, such as curtain rods and the like, from sheet-metals of all kinds where the nature of such articles is such that they must, at least in part, be formed of what is known as "dead-soft stock" but wherein other parts may be more advantageously composed of a metal possessing temper or its equivalent in order that the last named portions thereof may possess greater strength 15 and rigidity and may, therefore, be made of a very much thinner stock than would otherwise be required.

The main object of the invention is, therefore, to provide sheet metal articles such as 20 curtain-rods or channeled strips which, in ordinary use, are required to withstand substantially predetermined loads or stresses without becoming distorted and without sagging, from stock or blanks normally unsuited but rendered adaptable for the manufacture of such articles as above named, of a single piece of material, which stock or blanks is or are, respectively, of different degrees of hardness over different surface 25 areas to thereby permit sharp bending or folding of parts of the metal without breaking the same and permitting the forming of other portions thereof to curvatures as distinguished from sharp angles.

30 A further object of the invention is to provide sheet metal articles of the kind specified, wherein the temper, or its equivalent, is produced and regulated or controlled in degree by surface ornamentation mechanically applied thereto, to thereby render the articles far more attractive in appearance and lighter in weight proportionate to strength thereof than is true of such articles when made of dead-soft stock throughout.

The foregoing objects comprehend their accomplishment in a simple, cheap and practicable manner.

The invention consists in the product pos-

sessing the aforesaid characteristics as hereinafter fully described and claimed.

The invention is particularly illustrated in its accompanying drawings as embodied in curtain rods in connection with which it was developed, without, however, imposing limitations to the scope thereof as applied to articles, such as channeled strips or which are of a nature requiring the possession of the peculiar characteristics above mentioned to best adapt them for the performance of their intended functions.

In the accompanying drawings illustrating the invention—

Figs. 1 and 2 are, respectively, a fragmentary perspective view and a transverse section of a curtain rod made in accordance with the invention;

Fig. 3 is a fragmentary elevation of the blank or strip from which the rod is formed; Figs. 4, 5 and 6 and Figs. 7, 8 and 9, are, respectively, views similar to Figs. 1, 2 and 3, illustrative of other embodiments of the invention.

In said drawings, I have illustrated a very popular type of curtain rod (heretofore made of plain, smooth metal), the same being ornamented embodiments of any or all of the curtain rods illustrated in the catalog No. 11 of Kirsch Manufacturing Company, of Sturgis, Michigan, which is on file in the United States Patent Office (said rods being also shown in a number of Letters Patent of the United States Nos. 1,187,914, 1,240, 582, 1,245,354, 1,250,190, 1,488,256, 1,488,257, 1,488,258, 1,494,427, 1,494,428, 1,494,429 and 1,494,430), and differing in structural characteristics from all except Patent No. 1,494,430 only with respect to the double thickness of the flanges bordering the longitudinal slot in one wall of the rod, said double-thick flanged structure being disclosed in Patent No. 1,494,430.

The rods, generally termed "flat" as distinguished from the cylindrical or "round" type, comprise each, a flat front wall A, substantially semi-cylindrical side edges B which terminate in opposed flanges C substantially parallel with the wall A and having their free edges bordering the continuous slot D extending from end to end of the rod. Said free edges of said flanges C are of double thickness, being so made by folding over the extreme edge portions E

thereof, the structural advantages resulting from this double thickness being fully disclosed in said Letters Patent No. 1,494,430.

In practice it has been found very difficult 5 to produce rods having said double thick edged flanges for the reason that stock other than "dead-soft" would crack and break in the bending or folding operations. The necessity of using such "dead-soft" stock be- 10 cause of the very desirable structural feature last mentioned also necessitated the use of very heavy stock in order to provide sufficient stiffness and rigidity in the rod generally to adapt it to the ordinary conditions 15 of use, the tempered stock, such as half hard brass, for example, being far preferable to the soft stock because of its greater strength and resiliency, which resists distortion of all kinds. It has been found impossible to 20 so bend or fold the sheet steel used for the manufacture of the cheaper rods. This might be accomplished by the prohibitively expensive methods of annealing, forming and retempering with its attendant additional operations to correct warping and the 25 surface effects of heat, but such method is wholly impracticable aside from the expense attached thereto.

It will be understood from the foregoing 30 that the invention is particularly applicable to remedy conditions similar to those above described, wherein the body of an article of manufacture is most advantageously made of a hard, tempered stock which will not 35 permit of sharp bending, folding or the like, but a part or parts of which require the use of a very soft metal which will lend itself readily to such operations.

The invention consists essentially in pri- 40 marily producing sheet metal stock or blanks for the manufacture of articles of the general nature last above set forth, by mechanically thinning all of the areas of the dead-soft sheet or blank except those that 45 must remain dead-soft or substantially so. This may be accomplished in several different ways, depending, primarily, upon the construction of the finished articles to be produced from the sheet or blank.

In the case of curtain rods of the type 50 above described and illustrated in the drawings, it is most cheaply and best accomplished by first cutting a sheet of dead-soft stock into strips or blanks of the desired 55 shape and size and then passing said strips or blanks between two steel rolls, one there- 60 of having a smooth cylindrical face prefer- ably the exact width of the strip and the other thereof having a cylindrical face 65 formed with a pattern to be applied to one surface of the strip. The drawings ex- 70 amplely several of such patterns but, in each instance, the pattern impression avoids the respective side edge portions of the strip 75 over a width substantially double that of the

overturned edge flange E thereof. The im- 70 pression of the pattern effects a hardening of the patterned area of the strip. It also effects some elongation of the same and of the plain or unpatterned areas. The degree 75 of hardening effected is determined by the extent of the patterned area and the depth of the impression, the unpatterned areas remaining sufficiently soft to permit the sharp bending or folding thereof.

An alternative method is to first fold over the side edges of the strip and thereafter 80 impress the pattern into the desired area, and effect a forced elongation of the double thick portions by subjecting them to roller pressure tending to thin the same simultaneously with the impression of the pattern into the single thick area or portions thereof.

In the case of rods of the ordinary type, of single thickness throughout, the pattern 85 may cover the entire area of the strip or blank and its depth and extent determined by the degree of hardness desired to be im- 90 parted to the metal.

The hardness imparted by the above 90 method differs materially from so-called "temper" in that the metal possesses rigidity rather than resiliency. It is, therefore, bet- 95 ter adapted for curtain rods than a resilient stock for the reason that it is not so easily 100 flexed and is therefore not as liable to sag or twist under the influence of weight.

Curtain rods are generally made in two 100 distinct types, one being known as "tele- 105 scopically extensible" and the other as "cut- 110 to-fit." The latter are made only in long, straight lengths and adapted for cutting to any desired shorter pieces for assembly with end fittings to fit a window casing of given width. The "telescopically extensible" type, 115 on the other hand, is made up at the factory ready for the consumers' use without cutting, each unit consisting of two telescopi- 120 cally interfitted members, each of which ter- 125 minates in an end portion extending sub- 130 stantially perpendicularly to its main or telescopic portion, as shown in the catalog above referred to and in a number of my prior patents. (See U. S. Patents Nos. 1,187,914; 1,240,582; 1,245,354 and 1,250,190).

The bending of the telescopic type must 120 be effected after it is formed into straight lengths such as are illustrated in the drawings herewith and in the manufacture of this type of rod it is essential that the hard- 125 ness of the metal effected by the pattern impression shall not be too great to prevent such subsequent bending without resort to annealing. It is preferable, in the manufac- 130 ture of rods of this type, to adopt the gen- 135 eral class of patterns shown in Figs. 3 and 5 wherein alternate areas are left free of pat- 140 tern impressions as I find this preferable to patterning the whole area as exemplified in Fig. 1. This permits of a deeper pattern 145 130

impression in the pattern areas as distinguished from the plain areas, the latter obviously coacting with the pattern areas to produce attractive designs and effects, the 5 particular pattern to be imparted being determined with respect to proportions and relative locations of plain and depressed or pattern areas, by the particular conditions attending the further manipulation or forming of the strip or blank to produce the 10 finished article out of a single piece of metal.

While I have mentioned rolls for effecting the impressions, it will be obvious that any other means or devices adapted to the purpose 15 may be substituted for or used in conjunction with the rolls.

It will also be understood that depressions of any type may be substituted for those illustrated as it is the compression of the 20 metal, wholly independently of design, that determines the degree of hardness imparted to it, the employment of what may be termed "fanciful" impressions being merely selective and usually preferable to other types.

25 The product, as illustrated in the drawings, comprises a curtain rod or the like composed of a single piece of metal presenting soft edge portions and a harder intermediate area which may, at will, include 30 softer stripes or spots. It may also be defined as composed of dead-soft metal mechanically hardened to a predetermined degree, at least in part, and wherein such hardening is determined by the depth and area 35 of a fanciful pattern impressed into one face of the metal.

In carrying out the invention, it will be obvious that I not only gain in the stiffness or rigidity of the metal as well as the ornamentation thereof, but also gain from five 40 to ten per cent in the length of the strip or blank by elongation thereof, thereby obviously producing a lighter and stiffer structure at no appreciably greater cost than that 45 of the plain rods heretofore manufactured.

I claim as my invention:

1. A channelled structure, such as a curtain rod, formed of sheet metal normally soft to facilitate bending but insufficiently 50 rigid for ultimate purposes, strengthened and reinforced to the increased degree required by a distortion of the metal at spaced but closely associated points over the surface thereof, said distortion being constituted by an impressed design creating relatively condensed and uncondensed metal 55 areas.

2. A channelled structure, such as a curtain rod, formed of sheet metal normally soft to facilitate bending but insufficiently rigid for ultimate purposes, strengthened and reinforced to the increased degree required by a conjoint distortion and compression of the metal at spaced but closely associated points over the surface thereof thereby constituting alternate hard and soft areas. 60

65 3. A channelled structure, such as a curtain rod, formed of sheet metal normally too soft for ultimate purposes, compressed in spaced but closely associated areas to create the required rigidity and cooperate with the adjacent normal portions in creating a distinctive surface ornamentation. 70

4. A channelled structure, such as a curtain rod, formed of sheet metal possessing relatively soft and hard areas, soft areas 75 being disposed at the folds or bends, and the hard areas adjoining said last mentioned soft areas assisting in maintaining said folds or bends in predetermined position.

5. A channelled structure, such as a curtain rod, formed of sheet metal normally soft to facilitate bending but insufficiently rigid for ultimate purposes, hardened in spaced but closely associated areas to afford 85 the strength required, the hardened areas, also serving in creating surface ornamentation. 80

6. A channelled structure, such as a curtain rod, formed of sheet metal normally too soft for ultimate purposes, hardened in 90 spaced but closely associated areas to afford the strength required, the hardened areas also serving in creating surface ornamentation. 90

7. A channelled structure, such as a curtain rod, formed of sheet metal having alternate areas of varying degrees of hardness, the harder portions reinforcing the softer portions at the bends or folds. 95

8. A channelled structure, such as a curtain rod, formed of sheet metal having alternate areas of varying degrees of hardness, the harder portions cooperating with the softer portions to create rigidity throughout the structure. 100

9. A channelled structure, such as a curtain rod, formed of sheet metal having alternate areas of varying degrees of hardness, the harder portions reinforcing the body of the structure intermediate the 110 flanges thereof. 105

CHARLES W. KIRSCH.
